UNITED STATES PATENT OFFICE.

FRANK L. BURNS AND FREDERICK J. TESSIN, OF THREE RIVERS, MICHIGAN.

WIRE OR CABLE COUPLING.

1,427,258.

Specification of Letters Patent. Patented Aug. 29, 1922.

Application filed April 3, 1922. Serial No. 548,915.

To all whom it may concern:

Be it known that we, FRANK L. BURNS and FREDERICK J. TESSIN, citizens of the United States, residing at Three Rivers, 5 county of St. Joseph, State of Michigan, have invented certain new and useful Improvements in Wire or Cable Couplings, of which the following is a specification.

This invention relates to improvements in 10 wire or cable couplings.

It is the main object of this invention to provide an improved coupling for wire cables, brace wires and the like.

A further object is to provide an improved 15 coupling of this character which is composed of two duplicate parts and which may be joined to secure or clamp the wires connected without the employment of clamping bolts.

20 A still further object is to provide an improved coupling of this character which is easily engaged and disengaged as occasion may require but while engaged is very secure.

25 Further objects, and objects pertaining to details and economies of construction and operation will definitely appear from the detailed description to follow.

We accomplish the objects of our invention 30 by the devices and means described in the following specification. The invention is clearly defined and pointed out in the claims.

35 A structure which is a preferred embodiment of our invention is clearly illustrated in the accompanying drawing forming a part of this specification in which:

Fig. I is a side view of our improved coupling in operative relation on a cable.

40 Fig. II is a side view of one of the coupling members, the other being a duplicate thereof.

Fig. III is an end view of one of our improved coupling members the cable joined 45 being sectioned on a line corresponding to line 3-3 of Fig. 1.

Fig. IV is an inside view of one of the coupling members.

Fig. V is a cross section on a line corresponding to line 5-5 of Fig. I.

In the drawing the sectional views are taken looking in the direction of the little arrows at the ends of the section lines and similar numerals of reference refer to similar parts throughout the several views.

Referring to the drawing, the wires 1 to

be joined are illustrated as cables. These are shown conventionally as straight cables but it will be understood that our improved coupling is well adapted for use in braces, 60 guy wires and the like where one end of a cable is formed into a loop.

Our improved coupling comprises a pair of coupling members 3 each having a dove-tailed tapered rib 4 and an oppositely disposed dove-tailed tapered groove 5 adapted to receive the dove-tailed tapered rib of the coacting coupling member, a pair of the members being disposed in reversed relation and joined by a longitudinal movement, the tongue or rib of one member co-acting with the groove of the other.

Each coupling member has a longitudinal channel 6 disposed at each side of its center, the ribs and grooves being arranged in 75 the longitudinal centers of the coupling members. These channels are preferably roughened or spirally grooved to better grip the cables disposed therein. The ends of the coupling members are thickened or flared 80 outwardly at 7 to provide a thickened face or end which may be struck with a hammer or other tool in driving the coupling members together or in separating them.

In practice a pair of the coupling members are disposed on opposite sides of the wires to be connected with the wires lying in the channels 6. The coupling members are then clamped upon the wires by blows on the ends thereof which drive the tapered 85 dove-tailed ribs into the coacting grooves firmly clamping them upon the wires or cables. The pull upon the cable does not tend to disengage the coupling members as the pull on one cable is offset or counter- 90 acted by the pull on the other.

Our improved coupling is very economical to manufacture as the two parts are duplicates and, further, there are no small parts such as bolts or screws to become lost 100 or to manipulate in elevated or other inconvenient positions. Should a workman lose or drop one member any other coupling member of the same size can be utilized.

We have not attempted to illustrate or 105 point out the various adaptations or uses of our improved coupling as it is believed that the disclosure made will enable those skilled in the art to which our invention relates to embody or adapt the same as may be desired.

Having thus described the invention,

what is claimed as new and desired to secure by Letters Patent is:

1. A rod or wire coupling comprising a pair of coacting coupling members, each having an inwardly tapered dovetailed rib at one end and an aligned inwardly tapered dovetailed slot at the other end, the slot of one member being adapted to receive the rib of the coacting coupling member and each having a longitudinal wire clamping channel at the sides of its rib and groove.

2. A rod or wire coupling comprising a pair of coacting coupling members, each having an inwardly tapered dovetailed rib at one end and an aligned inwardly tapered dovetailed slot at the other end, the slot of one member being adapted to receive the rib of the coacting coupling member, said

members having opposed surfaces between which the parts to be joined are clamped. 20

3. A wire or rod coupling comprising a pair of coacting members, each having an inwardly tapered dove-tailed rib at one end and a longitudinally aligned inwardly tapered dove-tailed slot at the other end so 25 that the ribs of one member coact with the slot of the other when the members are joined by longitudinal movement, said members having opposed longitudinal channels adapted to receive the parts to be 30 joined.

In witness whereof, we have hereunto set our hands and seals.

FRANK L. BURNS. [L. S.]
FREDERICK J. TESSIN. [L. S.]
